[57] CLAIM

The ornamental design for a double-barreled pistol, substantially as shown and described.

DESCRIPTION

FIG. 1 is a top plan view of a pistol showing my new design;

FIG. 2 is a front elevational view thereof;

FIG. 3 is a side view thereof;

FIG. 4 is a bottom plan view thereof;

FIG. 5 is a rear elevational view thereof; and

FIG. 6 is a typical side view, the other side view being a mirror image thereof.
